(57) CLAIM

The ornamental design for a bedside caddy, as shown and described.

DESCRIPTION

FIG. 1 is a perspective view of a bedside caddy;

FIG. 2 is a front view of the bedside caddy;

FIG. 3 is a rear view of the bedside caddy;

FIG. 4 is a left side view of the bedside caddy;

FIG. 5 is a right side view of the bedside caddy;

FIG. 6 is top view of the bedside caddy; and,

FIG. 7 is a bottom view of the bedside caddy.

The broken lines in the figures represent portions of the bedside caddy that form no part of the claimed design.
